[57] **CLAIM**

The ornamental design for a spade-type boring bit, as shown and described.

DESCRIPTION

FIG. 1 is a front perspective view of a first embodiment of a spade-type boring bit embodying our new design; FIG. 2 is a rear elevational view thereof, taken from the side opposite that illustrated in FIG. 1; FIG. 3 is a side elevational view thereof, taken from the side opposite that illustrated in FIG. 1; FIG. 4 is a slightly enlarged top plan view thereof; FIG. 5 is a slightly enlarged bottom plan view thereof; FIG. 6 is a front perspective view of a second embodiment of our new design; FIG. 7 is a rear elevational view thereof, taken from the side opposite that illustrated in FIG. 6; FIG. 8 is a side elevational view thereof, taken from the side opposite that illustrated in FIG. 6; FIG. 9 is a slightly enlarged top plan view thereof; and, FIG. 10 is a slightly enlarged bottom plan view thereof. The broken lines in the Figures are shown for illustrative purposes only and form no part of the claimed design.
